UNITED STATES PATENT OFFICE.

WILLIAM A. PHILPOTT, JR., OF NIAGARA FALLS, NEW YORK, AND THOMAS A. BRIGGS, OF ARLINGTON, MASSACHUSETTS, ASSIGNORS TO THE STAND-ARD MACHINERY COMPANY, OF MYSTIC RIVER, CONNECTICUT.

PAPER-FEEDING MACHINE.

SPECIFICATION forming part of Letters Patent No. 626,631, dated June 6, 1899.

Application filed October 6, 1896. Serial No. 607,997. (No model.)

To all whom it may concern:

Be it known that we, WILLIAM A. PHILPOTT, Jr., of Niagara Falls, in the county of Niagara, in the State of New York, and THOMAS A. BRIGGS, of Arlington, in the county of Middlesex, in the State of Massachusetts, citizens of the United States, have invented new and useful Improvements in Paper-Feeding Machines, of which the following is a specification.

This invention relates to that class of sheet-paper-feeding machines in which the sheets are combed out and the top sheet is separated from the pile of sheets by a rotary comb-wheel, such a machine being shown, for instance, in Patent No. 538,640, granted to us April 30, 1895.

The objects of our invention are to improve the means whereby the sheets are fed from the upper supply to the lower feed-table, to render the machine capable of straightening or squaring the sheets transversely on the feed-table, to permit of easily adjusting the machine to different sizes of sheets, to provide means for preventing the sheets from being fed too rapidly against the front guides of the press and injured, to render the side-registering mechanism easily reversible for registering the sheets from either side, and to improve and simplify the construction of the machine in several details.

In the accompanying drawings, consisting of four sheets, Figure 1 is a horizontal section of our improved paper-feeder in line 1 1, Fig. 2. Figs. 2 and 3 are vertical longitudinal sections in lines 2 2 and 3 3, Fig. 1, respectively. Figs. 4 and 5 are fragmentary vertical longitudinal sections in lines 4 4 and 5 5, Fig. 11, respectively. Fig. 6 is an end elevation of our improved paper-feeder. Fig. 7 is a transverse section, on an enlarged scale, in line 7 7, Fig. 1. Fig. 8 is a horizontal section in line 8 8, Fig. 7. Fig. 9 is a side elevation, on an enlarged scale, of the abutment of the sheet-retarding mechanism and connecting parts. Fig. 10 is a top plan view of the same. Fig. 11 is a horizontal section in line 11 11, Fig. 4. Fig. 12 is a vertical longitudinal section, on an enlarged scale, in line

12 12, Fig. 1. Fig. 13 is a horizontal section in line 13 13, Fig. 12. Fig. 14 is a vertical transverse section in line 14 14, Fig. 12. Fig. 15 is a vertical section in line 15 15, Fig. 13. Fig. 16 is an inside elevation of one of the side plates of the feed-pawl carrier. 55

Like letters of reference refer to like parts in the several figures.

A represents the impression-cylinder of a printing-press provided with the usual grippers a, B the lower feed board or table arranged with its delivery end over the cylinder, and C the vertically-movable front registering-guides arranged over the cylinder and at the delivery end of the lower feed-board. 65

D is the upper feed or supply table, arranged at a suitable height above the lower table and secured to a frame d, which is pivoted at its delivery end by a transverse rod d' to standards or frames E E, mounted on the front or receiving portion of the lower table. The central and rear portions of the upper table are supported on each side by a pair of braces e e', pivotally connected at their upper ends to the supporting-frame d and pivotally connected at their lower ends with the adjacent standard by a link e'. 75

F represents the feed-belts whereby the body of the sheet-paper is carried from the upper supply-table to the lower feed-table 80 and which pass, with their receiving portions, around rollers g, arranged on the rear portion of the supply-table, thence forwardly over the supply-table, thence downwardly and rearwardly around feed-wheels G, which are 85 arranged between the delivery end of the upper table and the receiving end of the lower table, thence upwardly and rearwardly around supporting-rollers g', mounted on the under side of the upper table, and thence rearwardly 90 to the place of beginning. The pile of sheets is placed on the supply-table and the carrying portions of the belts, with the top of the pile tipped or combed rearwardly or toward the printing-press, and the front or bottom 95 portion of the pile is carried downwardly by the feed wheels and belts to the lower feed-table and moved forwardly over the latter in

an opposite direction from that in which it moves on the upper table, whereby the position of the sheets is reversed and the bottom sheet of the pile is arranged uppermost on the lower table. The feed-wheels are secured to a hollow transverse shaft g^2 , journaled with its ends on cylindrical bushings g^3 , which are secured in openings in the standards E.

H represents a number of curved guide-bands, which bear against the body of sheet-paper as it passes around the feed-wheels and which guides the paper from the feed-wheels to the lower table. The lower ends of these bands rest on the lower table and their upper ends are secured to hangers h, which are pivoted on a cross-bar h' , connecting the standards. The hangers of the outer guide-bands are provided with weighted arms h^2 , whereby the bands are pressed against the paper for increasing the frictional contact between the paper and the feed belts and wheels.

The construction and operation of all of the parts in the foregoing description are substantially the same as in Patent No. 538,640, heretofore referred to.

I represents pressure wheels or rollers whereby the body of sheets is pressed against some of the feed wheels and belts, so as to render the carrying effect of the belts and wheels more positive. One of these rollers is arranged above each of the inner feed-wheels and projects through a slot i, formed partly in the adjacent guide-band and the flange of its supporting-hanger. The pressure-rollers are secured to a transverse shaft i' , journaled in the free front ends of rock-arms i^2 , which are hung on the cross-bar h' and which permit the pressure-rollers to move toward and from the feed-wheels to adapt themselves to the variations in the thickness of the body of paper. The pressure-rollers are positively rotated in the direction of the arrow, Fig. 2, so as to aid in feeding the paper by means of a chain belt j, passing around a lower sprocket-wheel j' , secured to one end of the feed-wheel shaft, and an upper sprocket-wheel j^2 , journaled on the cross-bar h' , and intermeshing gear-wheels j^3 j^4 , secured, respectively, to the upper sprocket-wheel j^2 and one end of the pressure-roller shaft i' .

K K represent rotary bushing or combing wheels, which bear with their lower portions upon the sheets lying on the lower feed-table near the opposite side edges thereof and which comb out or separate the body of sheets and feed the top sheet toward the printing-press considerably in advance of the next lower sheet. Each of these combing-wheels is rotated intermittently and independent of the other wheel by the following mechanism:

L represents a short counter-shaft arranged parallel with and in rear of the feed-wheel shaft g^2 and journaled with its outer end in a bearing in the adjacent standard and with its inner end in a bearing formed in a bracket l, which is hung on the feed-wheel shaft and the cross rod or bar d'. l is a hollow rock-

arm, which is hung at one end on the counter-shaft and provided at its opposite free end with a bearing in which the shaft k of the comb-wheel is journaled. Motion is transmitted from the counter-shaft to the comb-wheel shaft by gearing which is arranged in the hollow arm and which consists of two gear-wheels l^2 , secured, respectively, to the counter-shaft and comb-wheel shaft and two intermeshing gear-wheels l^4 l^5 , which are journaled in the hollow arm and mesh, respectively, with the gear-wheels of the counter-shaft and the comb-wheel shaft. l⁶ is an idler gear-wheel journaled on an arbor secured to the outer side of one of the standards and meshing on one side with a gear-wheel l^7 , secured to the outer end of the counter-shaft and with its opposite side with a gear-wheel l^8 , which is journaled on one of the bushings g^3 , secured to the adjacent standard. M represents a continuously-rotating driving-shaft which is arranged in the hollow feed-wheel shaft g^2 and journaled concentrically in the bushings g^3 .

The driving mechanism of each comb-wheel is connected with and disconnected from the driving-shaft by a coupling device of any suitable construction, the preferred form of coupling for this purpose being an electromagnetic clutch which is shown in Figs. 13, 14, and 15 and constructed as follows:

N is a clutch-disk, of soft iron, journaled on one of the bushings g^3 and provided with a peripheral groove which contains a coil of insulated wire n. The clutch-disk is connected with the adjacent gear-wheel l^8 and is provided on its hub with two insulated metal collecting-rings n^1 n^2 , which are connected, respectively, with opposite ends of the coil of wire n. n^3 n^4 are two insulated brushes which bear, respectively, against the collecting-rings n^1 n^2 and which are in the circuit of an electric current. O is a clutch-wheel secured to the driving-shaft adjacent to the outer side of the clutch-disk and provided with a peripheral flange which overhangs the clutch-disk. o' represents a number of clutch-shoes, of soft iron, arranged between the flange of the clutch-wheel and the periphery of the clutch-disk, each shoe being loosely connected with the clutch-wheel by a radial pin o², secured to the flange of the clutch-wheel and engaging in a recess in the shoe, whereby the latter is compelled to turn with the clutch-wheel, but capable of moving radially toward and from the face of the clutch-disk. When the electric circuit which includes the coil of the clutch-disk is broken, the clutch-shoes are thrown outwardly by the rotation of the clutch-wheel and out of engagement with the clutch-disk, whereby the latter is disconnected from the driving-shaft and the movement of the comb-wheel is arrested. The instant the electric circuit is closed the clutch-disk becomes magnetized and draws the clutch-shoes against its periphery with sufficient force to couple the clutch disk and wheel,

120
130
135

thereby causing the movement of the driving-shaft to be transmitted to the comb-wheel through the medium of the intermediate connecting-gearing.

5 The feed wheels and belts are moved intermittently in unison with the comb-wheels by the following mechanism.

P represents a ratchet-wheel which is secured to one end of the feed-wheel shaft adjacent to the inner side of one of the standards E. Q is a feed-pawl carrier which is mounted on the rim of the ratchet-wheel and which consists of two side plates q and a transverse plate or body q', connecting the side plates. The inner side of each side plate is provided with a curved groove q², Fig. 16, the two grooved side plates forming jaws which loosely embrace the opposite curved edges of the ratchet-wheel rim, as represented in Fig. 13, whereby the pawl-carrier is held against lateral and radial movement on the ratchet-wheel, but is capable of sliding circumferentially thereon. The feed-pawls q³, Figs. 12 and 14, are pivoted to the front or upper ends of the side plates and are yieldingly held in engagement with the teeth of the ratchet-wheel by a spring q⁴, secured to the transverse plate. The pawl-carrier is arranged on the rear side of the ratchet-wheel, so that it has substantially a vertical movement and permits the return or downward movement thereof to be effected by gravity without the aid of springs. This manner of supporting the feed-pawls is extremely simple and inexpensive and is not liable to bind and get out of order. R is a rotary feed-cam which engages with a roller q⁵ on the rear or lower end of the pawl-carrier for moving the latter forward and turning the feed-wheels and which is journaled on an arbor r, secured to the inner side of the adjacent standard. The feed-cam is turned by intermeshing gear-wheels r' r², secured, respectively, to the counter-shaft and the feed-cam R, Figs. 13 and 14. r³ is an adjustable stop, whereby the effective or feeding movement of the pawl-carrier can be regulated. This stop consists of a rotary plate mounted loosely on the counter-shaft and provided with an eccentric or cam-shaped stop-face r⁴, against which a shoulder r⁵ on the back of the pawl-carrier is adapted to engage for limiting the backward movement of the pawl-carrier. The latter is always moved forward to the same point by the feed-cam; but its backward movement can be varied by turning the adjustable plate so that a higher or lower part of its stop-face engages with the shoulder of the pawl-carrier, whereby the extent of the effective movement of the pawl-carrier is varied. The stop-plate is provided with a thumb-piece r⁶ for adjusting the same and is held in its adjusted position by a clamping-screw r⁷, arranged in a bracket on the adjacent standard. S represents a detent-pawl carrier which is mounted on the upper portion of the ratchet-wheel and which consists of two side plates s, to

which the detent-pawls s' are pivoted, and a transverse plate s², connecting the side plates. The side plates are provided on their inner 70 sides with curved grooves, forming jaws which loosely embrace the opposite edges of the ratchet-wheel rim in the same manner in which the feed-pawl carrier is mounted on the ratchet-wheel. The detent-pawls are 75 yieldingly held in engagement with the teeth of the ratchet-wheel by a spring s³, secured to the detent-pawl carrier. When it is desired to utilize the detent-pawl to prevent backward movement of the ratchet-wheel, the 80 detent-pawl carrier is held against movement on the ratchet-wheel by means of a spring s⁴, which is secured to the transverse plate s² and which is provided with a seat s⁵, engaging with the cross-bar h'. Upon disengaging 85 the spring s⁴ from the rod h' the detent-pawl carrier can be oscillated on the rim of the ratchet-wheel by means of a handle s⁶ for adjusting the paper in the machine preparatory to starting the automatic feeding of the 90 sheets.

Each sheet as it is fed by the comb-wheels over the lower feed-table toward the printing-press passes between two pair of contacts, which are arranged to engage with the front 95 edge of the sheet near the opposite front corners thereof. Each pair of contacts consist, preferably, of a lower metal roller t, which is journaled in the lower feed-table below the path of the sheets, and an upper metal roller 100 t', which is yieldingly held in contact with the lower roller. The upper contact is connected by a wire t² with one pole of an electric generator T, the other pole of which is connected by a wire t³ with the brush n³ of one 105 of the electric clutches. t⁴ is a metal supporting-rod, to the lower end of which the upper contact-roller is pivotally connected by a metal link t⁵, and t⁶ is a spring secured at one end to said rod and bearing with its opposite end against the link for keeping the upper roller t' in contact with the lower roller t. The lower contact or its support is connected by a wire t⁷ with the other brush n⁴ of the aforesaid electric clutch. t⁸ is a transverse supporting-bar which carries the supporting-rod t⁹ of both upper contacts and which is secured by insulation at its ends to standards t¹⁰, arranged on the lower feed-table. When both upper contact-rollers bear against both lower contact-rollers, the electric circuits of both clutches are closed and both 115 comb-wheels are coupled with the driving-shaft, which causes both comb-wheels to rotate and feed a sheet forwardly. When the 120 comb-wheels leave the rear edge or margin of the top sheet, the front edge of the latter has been moved between the upper and lower rollers of both contacts and the paper serving as an insulator breaks both electric circuits, 125 thereby uncoupling both clutches and arresting the movement of both comb-wheels and the forward feed of the sheets. If a sheet is 130 fed forward obliquely, the foremost corner of

the sheet passes between one pair of contacts and arrests the movement of the comb-wheel which feeds that side of the sheet, while the other comb-wheel continues to rotate until 5 the opposite side of the sheet has also been fed forward until its front edge also separates the other pair of contacts. By this means any irregularity in the feeding of the sheets is corrected and the sheets are always squared 10 or straightened on the feed-table. After the front edge of the sheet has separated the contacts of both pairs and has arrested the movement of the comb-wheels the sheet is carried toward the press by a separate carrying device, and when the rear edge of the sheet 15 clears the contacts the upper contact-rollers are instantly pressed against the lower contact-rollers and the feeding movement of the comb-wheels and feed-wheels is resumed until the front edge of the next sheet has been 20 fed between both pairs of contacts.

The relative position of the comb-wheels and the electric contacts is such that when 25 the front edge of the top sheet has separated the upper and lower contacts the comb-wheels have cleared the rear edge of the top sheet and bear upon the next sheet below the top sheet to prevent the lower sheet from being carried away with the top sheet. In order to 30 permit of feeding sheets of various lengths, the comb-wheels are adjusted lengthwise on the lower feed-table toward and from the electric contacts for adapting the comb-wheels to the sheets. For the purpose of accomplishing this result in a simple and expeditious 35 manner the standards E, upon which the sheet-separating mechanism is mounted, are made longitudinally adjustable on the lower feed-table. As shown in the drawings, the lower 40 end of each standard is provided with a foot or flange u on its inner side, which slides on a longitudinal rail or track u' , secured to the top of the lower feed-table, and the rail is provided with an angular retaining-bar u^2 , 45 which overhangs the foot of the standard, whereby the standard is held against displacement on the lower table. The standards are shifted by means of a transverse adjusting-shaft u^3 , journaled in the lower portion 50 of both standards E and provided adjacent to the inner sides of the standards with gear-pinions u^4 , which mesh with gear-racks u^5 , secured lengthwise to the top of the feed-table. One end of the adjusting-shaft is provided 55 with a hand-wheel u^6 for turning this shaft, and the inner side of one of the standards is provided with a retaining-pawl u^7 , which is adapted to engage with one of the gear-pinions u^4 and hold the adjusting-shaft 60 against turning after the parts are adjusted. It has been found in practice that the comb-wheels must be placed sufficiently near to the feed-wheels to enable the comb-wheels to obtain control of the sheets before 65 the latter leave the feed-wheels, so as to prevent the sheets from shifting. For this purpose the comb-wheels are placed near enough

to the feed-wheels to retain control of the narrowest sheets, which are intended to be fed by the machine. By shifting the feed-wheels, together with the comb-wheels, the relative position of these parts is never disturbed, and a simple and non-adjustable drive mechanism can be employed for driving the comb-wheels, which insures transverse 75 alinement of both comb-wheels at all times without any care on the part of the operator.

V represents two rapidly-rotating feed-rollers, which rotate at about the rate of six revolutions to one of the impression-cylinder, and 80 whereby each sheet is carried toward the printing-press after its front edge has been fed between the electric contacts by the comb-wheels. These rollers are mounted on a continuously-rotating shaft v , which is journaled 85 in bearings on the under side of the feed-table and protrude upwardly through openings in the feed-board adjacent to the contacts, so that their uppermost portions are in line with the top of the table. v' are two 90 presser or drop rollers arranged above the feed-rollers V and having a vertical movement toward and from the feed-rollers. Each of these presser-rollers is mounted on a forwardly-projecting rock-arm v^2 , which is secured to a transverse rock-shaft v^3 , journaled in the standards t^4 . The pressure-rollers are raised and lowered once during each impression of the printing-cylinder. During the time that the sheet is being fed forward to 100 the electric contacts the presser-rollers are elevated, and after the sheet has been fed between the contacts the drop-rollers descend and press the sheet against the feed-rollers, whereby the latter are caused to carry the 105 sheet rapidly toward the drop-guides of the printing-press. When the sheet has been fed forward a sufficient distance by the feed-rollers, the presser-rollers are again raised. The means shown in the drawings for raising and 110 lowering the presser-rollers consist of a vertical bar or rod v^4 , connected at its upper end to a rearwardly-projecting rock-arm v^5 on the rock-shaft and a cam v^6 , engaging with a roller or projection on the lower end of said rod. 115 This cam is mounted on a counter-shaft v^7 , which is journaled in bearings on the under side of the feed-table and which is driven from the shaft of the feed-rollers V by a train of speed-reducing gear-wheels v^8 .

In order to prevent the sheets from being fed by the rapidly-rotating feed-rollers V against the front or drop guides with a speed sufficient to injure the front edge of the sheets, the speed of the latter as they approach the drop-guides is reduced or slackened by a retarding mechanism, which is constructed as follows:

W represents two eccentric rollers, which are mounted on a transverse shaft w , journaled in bearings on the under side of the feed-table and which are adapted to protrude upwardly through openings w' in the feed-table. These eccentric rollers are rotated

once during each impression of the printing-cylinder in any suitable manner—for instance, by means of a chain belt w^2 , passing around sprocket-wheels $w^3 w^4$, mounted, respectively, on the counter-shaft v^7 and the eccentric roller-shaft. w^5 represents two abutment-rollers, which are arranged above the path of the sheets vertically in line with the eccentric rollers and against which each sheet is pressed by the eccentric rollers during the last portion of the movement of the sheet toward the front drop-guides. Each of the abutment-rollers is mounted on the rear arm of an adjusting-lever w^6 , which is pivoted on a transverse arbor w^7 , secured to a longitudinal supporting-plate w^8 , as shown in Figs. 9 and 10. The abutment-roller is yieldingly held in a depressed position by a spring w^9 , surrounding the arbor w^7 and secured with its ends to the adjusting-lever, and a rotary thumb-piece w^{10} , mounted on the end of the arbor. The extent of the downward movement of the abutment-roller is regulated by means of an adjusting-screw w^{11} , which bears against the upper side of the front arm of the adjusting-lever and which engages with a screw-threaded opening formed in a lug arranged on the supporting-plate. The instant the drop-rollers are raised, so that the sheet clears the rapidly-rotating feed-rollers, the slowly-rotating eccentric rollers begin to press the sheet against the abutment-rollers, whereby the speed of the sheet is checked and the sheet is fed slowly against the front guides without kinking the front edge thereof. As the eccentric rollers bear against the abutment-rollers the latter rise and fall in adjusting themselves to the peripheral faces of the eccentric rollers, which movement of the abutment-rollers is permitted by their yielding supports. Upon adjusting the abutment-rollers upwardly, so as to increase the distance between the same and the eccentric rollers, the peripheral faces of the latter remain during each rotation in contact with the abutment-rollers a comparatively short time, whereby the sheets are acted upon by the eccentric and abutment rollers only during a short part of their movement. When the abutment-rollers are adjusted toward the eccentric rollers, the duration of contact between the sheets and the abutment and eccentric rollers is increased and the sheets are fed forward by these rollers a correspondingly greater distance, so that by adjusting the abutment-rollers with reference to the eccentric rollers the carrying effect of these rollers can be regulated for feeding sheets of different widths properly to the front guides. Each of the supporting-plates is secured to a longitudinal supporting-rod w^{12} , which is hung with its front end on the cross-bar t^8 and secured with its rear end to a transverse supporting-bar w^{13} . The latter is supported at its ends by means of posts w^{14} , arranged on the feed-table.

X' represent two side-registering devices

whereby the sheet may be side-registered on either of its side edges and which are arranged on the feed-table on opposite sides of the path of the sheet. These side-registering devices are provided with side guides x^x , against either of which the sheets are drawn by a transversely-reciprocating carrier-bar x^2 , that operates the gripping devices. The construction and operation of this side-registering device are fully described in Letters Patent No. 562,797, granted to us June 30, 1896, to which reference may be had for the details of construction. In the operation of this side-registering mechanism the gripper adjacent to that side of the sheet on which the latter is to be registered is first moved inwardly or away from the side guide and is then moved outwardly, during which latter movement the working gripper grasps the sheet and draws its side edge against the registering side guide. If it is desired to change the registering of the sheets from one side to the other, the movement of the carrier-bar must be altered, so that its first or inward movement will be away from the registering side guide, and for the purpose of enabling the operation of the side-registering mechanism to be readily and accurately shifted for changing the register of the sheets from one side to another the following mechanism is provided:

Y represents a vertical rock-spindle, which is journaled in a bracket y , secured to the under side of the feed-table and which is provided at its upper end with a crank-disk y' . y^2 is a connecting-rod pivoted at one end to a crank-pin y^3 on the crank-disk and pivoted with its opposite end to a pin y^4 , which is secured to the under side of the carrier-bar and projects downwardly through a slot y^5 in the feed-table. y^6 is a gear-pinion which is mounted loosely on the spindle and confined against longitudinal movement on the spindle by shoulders formed on the bracket on opposite sides of the pinion. y^7 is a horizontal reciprocating gear-rack guided on the bracket and meshing with the outer side of the gear-pinion. This gear-rack is actuated from a cam y^8 on the counter-shaft v^7 by a connecting-rod y^9 , which is pivoted at its rear end to the gear-rack and provided at its front end with a roller or pin y^{10} , engaging with the cam-groove y^{11} and with a slot y^{12} , whereby the connecting-rod is guided on the counter-shaft. z represents a coupling-sleeve whereby the spindle and the gear-pinion are coupled and which surrounds the spindle below the pinion and is journaled in the adjacent portion of the bracket. This sleeve is capable of lengthwise movement on the spindle, but is compelled to turn therewith by means of a transverse pin z' , secured to the spindle and engaging with longitudinal slots in diametrically opposite sides of the lower end of the coupling-sleeve. z^2 is a pin arranged at the inner end of the coupling-sleeve and engaging with one of two recesses or openings z^3 ,

which are formed in the underside of the pinion on diametrically opposite sides thereof. This pin is yieldingly held in engagement with one of the openings in the pinion by 5 means of a spring z^4 , which surrounds the spindle within the enlarged lower portion of the coupling-sleeve and bears with its ends against a shoulder on the coupling-sleeve and a collar z^5 on the lower end of the spindle.

10 Figs. 4, 7, 8, and 11 show the position of the parts of the side-registering mechanism preparatory to beginning the operation of registering a sheet on the left-hand edge. Before the sheet has been fed against the front guides, 15 the cam y^8 first moves the gear-rack, pinion, carrier-bar, and connecting parts forward in the direction of the arrows, Figs. 1, 4, 7, 8, and 11, and after the sheet has been fed against the front guides the cam moves these parts 20 backward and the sheet is carried outwardly by the gripper of the registering device X against the registering-guide x . The registering mechanism now remains at rest until the registered sheet has been carried away by 25 the grippers of the press. When registering the sheets on the left-hand edge, the crank-pin on the crank-disk moves in an arc on the rear portion of the disk from the point z^6 to the point z^7 and then back again to the point 30 z^6 , as shown in Fig. 11. When it is desired to reverse the movement of the registering device, so as to side-register the sheet from the right-hand side, the throw of the crank-disk must be changed so that its crank-pin 35 during the registering operation first moves forward in an arc on the front portion of the disk from the point z^8 to the point z^9 and then back again to the point z^8 , as shown in Fig. 11, whereby the movement of the carrier-bar 40 is changed, so that it first moves inwardly from the side-registering device X' and then outwardly for carrying the right-hand edge of the sheet against the side guide X' . This change in the register of the sheet from one 45 side to the other is accomplished by pulling the coupling-sleeve downwardly until its pin is disengaged from the respective recess in the gear-pinion, then turning the coupling-sleeve, spindle, and crank-disk one-half 50 around independent of the gear-pinion, and then releasing the coupling-sleeve, so that its pin engages with the other recess of the pinion, whereby the connecting-rod, carrier-bar, and connecting parts are shifted into the 55 proper position for reversing the side-register of the sheets.

We claim as our invention—

1. The combination with the feed-table, the supply-table and the feed-wheels arranged at 60 one end of the supply-table and adapted to feed the sheets from the supply-table to the feed-table, of a pressure-roller which bears against the sheets as they pass from the supply-table to the feed-table, a rocking support 65 in which said roller is mounted, a gear-wheel mounted concentric with said roller, an intermeshing gear-wheel mounted concentric with

the pivot of said rocking support, and a driving mechanism whereby said intermeshing gear-wheel is driven from the shaft of said 70 feed-wheels, substantially as set forth.

2. The combination with the lower feed-table, the upper supply-table and the feed-wheels arranged on a shaft at one end of the supply-table and adapted to feed the sheets 75 from the upper to the lower table, of pressure-rollers bearing against the sheets as the latter pass over the feed-rollers and mounted on a transverse shaft, rock-arms provided with bearings in which the pressure-roller shaft is 80 journaled and hung upon a supporting-rod, a chain belt passing around sprocket-wheels mounted, respectively, on the feed-wheel shaft and the supporting-rod, and intermeshing gear-wheels secured, respectively, to the 85 pressure-roller shaft and the sprocket-wheel mounted on the supporting-rod, substantially as set forth.

3. The combination with the frame, the lower feed-table, the upper supply-table, and 90 the feed-wheels whereby the sheets are fed from the upper to the lower table, of a hollow shaft journaled on the frame and supporting the feed-wheels, a driving-shaft arranged within the feed-wheel shaft, and a coupling 95 whereby the driving-shaft and the feed-wheel shaft may be connected or disconnected, substantially as set forth.

4. In a paper-feeder, the combination with the main frame, the feed-wheel shaft and the 100 ratchet-wheel mounted thereon, of a pawl-carrier supported on the rim of the ratchet-wheel, and a spring secured to the pawl-carrier and engaging yieldingly with the main frame, substantially as set forth. 105

5. In a sheet-paper feeder, the combination with a feed-table, a combing-wheel whereby the sheets are fed off and a feed-wheel whereby the sheets are moved to the feed-table, of a support in which said combing-wheel and 110 feed-wheel are mounted and which is adjustable toward and from the front end of the feed-table, whereby the combing-wheel and feed-wheel are simultaneously adjusted while retaining their position relatively to each 115 other, substantially as set forth.

6. In a sheet-paper feeder, the combination with a lower feed-table, of an upper supply-table, a feed-wheel whereby the sheets are moved from the supply-table to the feed-table, 120 a comb-wheel whereby the sheets are fed off, and a support on which said supply-table, feed-wheel and comb-wheel are mounted and which is adjustable toward and from the front end of the feed-table, substantially as set 125 forth.

7. In a sheet-paper feeder, the combination with the lower feed-table, the upper supply-table, and the sheet separating and propelling devices, of controlling devices arranged on 130 the feed-table in advance of the separating and propelling devices and adapted to control the latter and a frame supporting the supply-table and the sheet separating and

propelling devices and capable of adjustment toward and from the controlling devices, substantially as set forth.

8. In a sheet-paper feeder, the combination with the lower feed-table, and the sheet separating and propelling devices, of controlling devices arranged on the feed-table in advance of the separating and propelling devices and adapted to control the latter, a frame supporting the separating and propelling devices and capable of longitudinal adjustment on the feed-table toward and from the controlling devices, and an adjusting-shaft journaled transversely in bearings on the movable frame and provided with gear-wheels meshing with gear-racks on the feed-table, substantially as set forth.

9. The combination with the sheet-feeding mechanism, of an eccentric feed-roller arranged on one side of the path of the sheets and an abutment on the opposite side of the path of the sheets arranged to adapt itself to the eccentric face of said roller, substantially as set forth.

10. The combination with the sheet-feeding mechanism, of an eccentric feed-roller arranged on one side of the path of the sheets, an abutment on the opposite side of said path arranged to adapt itself to the eccentric face of said roller, and means whereby the movement of the abutment toward the roller can be regulated to call a greater or less portion of the face of the roller into action, substantially as set forth.

11. The combination with the sheet-feeding mechanism, of an abutment arranged on one side of the path of the sheets, an eccentric roller arranged on the opposite side of the path of the sheets and adapted to bear against the abutment, a rock-lever pivoted on a support and carrying the abutment on one of its arms, a spring whereby the abutment is yieldingly pressed toward the eccentric roller, and an adjusting-screw mounted on said support and bearing against the other arm of the rock-lever for regulating the movement of the abutment toward the eccentric roller, substantially as set forth.

12. The combination with the side-registering mechanism and the reciprocating rod whereby the side-registering mechanism is operated, of a rotary spindle connected with said reciprocating rod, a driving-wheel mounted loosely on said spindle, and a coupling-sleeve capable of sliding lengthwise on the spindle

but compelled to turn therewith and adapted to be engaged with or disengaged from the driving-wheel, substantially as set forth.

13. In a paper-feeder, the combination with the side-registering mechanism and the reciprocating carrier-bar whereby the side-registering mechanism is operated, of a rock-spindle provided with a gear-wheel and a crank-pin, a link connecting the crank-pin with the carrier-bar, and a reciprocating gear-rack meshing with the gear-wheel, substantially as set forth.

14. In a paper-feeder, the combination with the side-registering mechanism and the reciprocating carrier-bar whereby the side-registering mechanism is operated, of a rock-spindle provided with a crank-pin, a link connecting the crank-pin with the carrier-bar, a gear-wheel mounted loosely on said spindle and provided with two openings arranged on diametrically opposite sides, a coupling-sleeve capable of sliding lengthwise on the spindle but compelled to turn therewith and provided with a pin adapted to engage with one of the openings in the gear-wheel, and a reciprocating gear-rack meshing with said gear-wheel, substantially as set forth.

15. In a paper-feeder, the combination with the side-registering mechanism and the reciprocating carrier-bar whereby the side-registering mechanism is operated, of a rock-spindle provided with a crank-pin, a link connecting the crank-pin with the carrier-bar, a gear-wheel mounted loosely on said spindle and provided with two openings arranged on diametrically opposite sides, a coupling-sleeve capable of sliding lengthwise on the spindle but compelled to turn therewith and provided with a pin adapted to engage with one of the openings in the gear-wheel, and a spring whereby the coupling-sleeve is pressed toward the gear-wheel, substantially as set forth.

Witness our hands this 22d day of September, 1896, and 3d day of October, 1896.
